UNITED STATES PATENT OFFICE.

JAY DAVID THOMAS, OF PUEBLO, COLORADO, ASSIGNOR TO AMERICAN SMELTING AND REFINING COMPANY, OF NEW YORK, N. Y., A CORPORATION OF NEW JERSEY.

METHOD FOR CHARGING FURNACES.

Application filed January 11, 1921. Serial No. 436,437.

To all whom it may concern:

Be it known that I, JAY DAVID THOMAS, a citizen of the United States, and resident of Pueblo, in the county of Pueblo and State 5 of Colorado, have invented certain new and useful Improvements in Methods for Charging Furnaces, of which the following is a specification.

The invention relates to an improvement 10 in the metallurgical art of charging metallurgical furnaces and like ore receiving receptacles, and more specifically relates to an improved method for charging the retorts of zinc furnaces and to an improved form 15 of instrumentality for efficiently practicing the method.

In the art of charging metallurgical furnaces it is necessary to handle heavy and sometimes semi-plastic ores while they are 20 in a moist condition. This character of ore is obviously difficult to measure and does not lend itself readily to any usual methods of controlling the charge admitted to the furnace. For instance, any attempt to feed this 25 ore in a continuous stream has proven impractical, among other reasons, due to the fact that the ore tends to choke up in the conducting passageways and any device depending on the handling of a continuous 30 stream of such material quickly becomes inoperative.

One of the objects of the present invention therefore, is to suggest a simple and readily actuated method for feeding a regulated 35 charge of ore of the character discussed, to the furnace or other receptacle and under conditions which will permit of regulation and control of the charge and which will eliminate the heretofore objectionable clog- 40 ging of the feeding machine.

I attain this phase of the invention by preforming the ore into relatively small separated charges of approximately the same mass and configuration and which charges 45 will hereinafter be identified as "ore bullets" due to their functioning as bullets when admitted to a compressed fluid actuated gun hereinafter described. It is then proposed to blow these separated bullets into the re- 50 ceiving furnace by means of steam pressure which acts in three ways: first, as a propelling medium, second, to provide a steam cushion between succeeding charges as they pass from the discharging machine 55 into the furnace, and third, in the act of

condensing under the conditions present it provides both a lubricant to the moving ore bullets and, finally supplies the requisite moisture desirable in the charge in certain metallurgical operations.

Various other objects and advantages of the invention will be in part obvious from an inspection of the accompanying drawings and in part will be more fully set forth in the following particular description of one form of mechanism for carrying out my invention.

In the drawings:—

Figure 1 is a view largely diagrammatic showing in end elevation a preferred embodiment of the invention disposed in position to supply a battery of retorts in a zinc furnace shown in vertical section;

Figure 2 is a view in side elevation of the device shown in Figure 1 looking at the same 75 from the right hand side;

Figure 3 is an enlarged detail vertical view taken on the line 3—3 of Figure 2 and

Figure 4 is an enlarged view in side elevation of the feed wheel shown in axial 80 section in Figure 3.

Referring to Figure 1 there is shown a zinc furnace A, provided with a battery of retorts B designed to be supplied with ore from the machine. The machine is carried on a car 10 mounted on tracks 11 which extend lengthwise of the zinc furnace so as to be in proper position opposite the different retorts to supply the same. The car 10 is provided with transversely disposed tracks 12 on which is mounted a carriage 13 for supporting the different mechanical parts of the machine. The ore charge is supplied to an ore hopper 14, the discharge from which is regulated by gates 15. The hopper discharges into a throat 16 of a single screw conveyor ore feeder 17 which extends horizontally of and lengthwise of the machine so as to provide a length of screw sufficient to insure a constant and uniform supply of the ore at its discharge end.

The discharge end of this conveyor is provided with a discharge port 18 which leads, as shown in Figure 3, to the periphery of the feed wheel 19 mounted for rotary movement in the bullet forming machine 20. The wheel as shown in Figure 4, is provided with a plurality of pockets 21 circumferentially spaced apart and providing teeth 22 therebetween which consti- 111

tute valves for intercepting the flow of steam through the steam gun 23. This gun includes a straight bore formed in the lower portion of the charging machine and in an 5 ore pipe 24 which extends therefrom and beyond the outlines of the machine as shown in Figure 1. It is understood that the configuration of the pockets 21, the size and speed of rotation of the feed wheel controls 10 the size of the ore bullets and the rate at which they are fed to the steam gun and also controls the rate at which the formed 15 bullets are fed to the furnace.

A source of high pressure steam supply, 20 indicated symbolically by the steam pipe 25, leads into the charging machine in alignment with the bore in the ore pipe 24 and the steam pressure acting through the gun is controlled by any suitable means such 25 as by the manually actuated valve 26.

Power is supplied to the apparatus by means of an electric motor 27 connected to a counter shaft 28 through a chain drive 29, and through the chain drive 30 counter- 30 shaft 28 drives the shaft 31 through gear 32. The screw feeder 17 is coupled to the shaft 31 by means of a chain drive 33, and the parts as so geared together and proportioned that all of the pockets of the feed wheel will be filled completely with ore from the screw feed as each pocket in succession is brought into position beneath the opening 18.

The discharge end 34 of the ore pipe projects a material distance from the machine so as to be advanced into the zinc furnace as shown in ghost lines in Figure 1. The ore pipe is provided adjacent its discharge end with a water pipe 35 by means of which 40 the proper amount of moisture may be added to the charge just before the ore bullets are ejected from the steam gun.

In operation and assuming that the hopper 14 is charged with ore and that the gates 15 are regulated to supply the requisite amount of ore to the screw conveyor, the machine is set in motion. The ore is conveyed by the screw from the right to left of the showing in Figure 1, and is 45 deposited as shown by the arrows in Figure 3 into each of the succeeding pockets 21 as they come uppermost in the charging machine. The ore will be packed into the feed wheel with a pressure depending upon 50 the rate of speed of the conveyor and the ore bullets formed in the compartment are carried downwardly with the rotation of the runner and successively positioned in the steam gun in advance of the discharge 55 end of the steam inlet 26. The steam pressure from the pipe 25 acts on each succeeding bullet, forces the same along the ore pipe and discharges the same into one of the retorts B. After a bullet has been discharged from the revolving wheel the next

succeeding tooth 22 moves across the discharge end of the steam inlet thus momentarily shutting off the steam supply from the gun. This action causes the steam momentarily to build up its pressure at the discharge end of the steam pipe which accumulated pressure is immediately and conveniently available to exert its propelling effect on the next bullet brought into position into the gun by the rotating wheel. 70 The action is repeated, it being understood that each bullet follows the preceding bullet in rapid succession simulating the action of a rapid firing machine gun. Each bullet is separated from the succeeding bullet in the ore pipe by a charge of steam under high pressure. The steam not only acts as the propelling medium but acts to lubricate the interior of the bore of the ore pipe and provides a layer of steam between the moving ore bullets and the inner wall of the ore pipe. As the ore charges pass the discharge end of the water pipe 35 they are supplied with the requisite amount of water. It will be understood that the action of the cold ore, either with or without the addition of the water supplied thereto by the pipe 35, acts on the propelling steam to condense the same, so that, by the time the ore charge reaches the retort, the steam has largely lost its propelling effect. 85 90 95

It is readily appreciated that by a suitable control of the speed of the motor 27 and of the open position of the valve 26, an accurate control is provided for regulating the rapidity with which the charges are fed to the retort and the steam pressure can be so regulated as to effect a clearing of the ore pipe economically and without the use 100 of unnecessarily high pressures.

By means of the method disclosed it has been found possible to provide an accurately controlled supply for feeding zinc furnaces and like metallurgical receptacles, clogging has been eliminated and the proper control of the moisture element is provided. 110

While I have shown and described and have pointed out in the annexed claims certain novel features of my invention, it will be understood that various omissions, substitutions and changes in the process and in its operation may be made by those skilled in the art without departing from the spirit of the invention. 115

Having thus described my invention, I claim:

1. In the art of charging zinc retorts with moist ore, the method which consists in feeding a continuous stream of measured and separated bullets of zinc-containing-ore to the retorts, and with the spaces in the stream between the spaced bullets filled with steam under pressure thereby to form steam cushions for keeping the bullets separated. 120

2. In the art of charging zinc retorts with moist ore, the method which consists in feeding a continuous stream of preformed separated bullets of zinc-containing-ore to the 5 retorts, and with the spaces in the stream between the spaced bullets filled with steam under pressure thereby to form steam cushions for keeping the bullets separated and introducing water to the bullet stream.
- 10 3. In the art of charging zinc retorts with moist ore, the method which consists in forming a stream of cold bullets of zinc-containing ore each bullet having approximately the same mass subjecting the bullets 15 of the stream successively to the propelling influence of a jet of steam in a direction to propel the bullets in a steam actuated stream into the retorts, and permitting said cold ore to condense the steam in engagement therewith in the retort thereby to prevent the formation of back pressures on the ore bullets and 20 causing the resulting vapor to escape from the retorts without appreciable pressure.
4. In the art of charging zinc retorts with moist ore, the method which consists in forming a stream of cold bullets of zinc-containing ore each bullet having approximately the same mass subjecting the bullets 25 of the stream successively to the propelling influence of a jet of steam in a direction to propel the bullets in a steam actuated stream into the retorts, and permitting said cold ore to condense the steam in engagement therewith in the retort thereby to prevent the formation of back pressures on the ore bullets.
5. In the art of charging zinc retorts, the method which consists in abstracting from a stream of the ore to be fed to the retort, 30 a measured amount to form a compact bullet, and blowing said bullet as a single unit into the retort.

Signed at Pueblo in the county of Pueblo and State of Colorado this 29th day of December, A. D. 1920.

JAY DAVID THOMAS.
